JAPANESE TISSUE MILLS, OF HOLYOKE, MASSACHUSETTS, A CORPORATION OF MAS-
SACHUSETTS.

FEEDING AND DRYING APPARATUS FOR PAPER MACHINES.

992,688.

Specification of Letters Patent. Patented May 16, 1911.

Application filed March 28, 1910. Serial No. 551,991.

To all whom it may concern:

Be it known that I, CHARLES ELMER POPE, a citizen of the United States of America, and resident of Holyoke, in the county of 5 Hampden and State of Massachusetts, have invented certain new and useful Improvements in Feeding and Drying Apparatuses for Paper-Machines, of which the following is a full, clear, and exact description.

10 This invention relates to paper machines, and more especially to that class thereof in which the paper after it has left the so called Fourdrinier machines is thoroughly dried preparatory to the subjection thereof to the 15 calendering rolls, and it has for one of its objects the provision, in connection with suitable drying rolls, of means whereby the web of the paper, in case it should break, will be automatically brought into recontact with said rolls so that the feeding operation of the paper through this machine will be practically continuous and without requiring any manual assistance to perform this work.

25 The present improvement is particularly applicable to machines in which very thin paper such as tissue and the like is handled, in which case, by virtue of its thin texture, breakages of the web are very liable to occur, and in which the subsequent rethreading or reintroduction into contact with the roll next succeeding the break in the web is a comparatively difficult operation.

In the present instance I employ in connection with the drying rolls, an endless apron which passes around said rolls in succession and which brings the paper to be dried into contact with the several rolls, and the several rolls are also provided with what 10 might be called scrapers whereby the paper is positively disengaged from said rolls and which at the same time serve as means for guiding the web if it should break, the latter being blown against these plates by an air current the tendency of which is to blow the paper again into contact with the band which will then pick the same up and thread it into contact with the next succeeding drying roll. Furthermore, means are provided 15 whereby the end of the paper as it emerges from the last drying roll of the series, will be guided and blown between the first pair of cooperative calendering rolls in an en-

tirely automatic manner so that the manual threading of the web in the last named machine will be obviated.

The invention has been clearly illustrated in the accompanying drawing in which the machine is illustrated in diagrammatic form, and in which 10 and 11 denote the last pair or drawing-out rolls of a Fourdrinier machine which, furthermore, comprises a band 12 of hard felt and a similar band 13 of soft felt. Experience has demonstrated the fact that the paper issuing from this machine will adhere to the hard felt, and consequently the drying rolls which constitute part of the present invention are disposed so as to be coöperative with the hard felt band 12 which is conducted over a roller 14 and also an adjustable straight roll 15, that portion of the band 14 which is disposed between said rolls 14 and 15, being in peripheral contact with the first one of a series of drying rolls indicated herein by 15 D, D' which are journaled in a suitable frame shown in dot-and-dash lines f in the drawing and which may be heated through the introduction of steam into the hollow interior thereof.

Traveling over the rollers D is an endless apron or band 20 which is conducted over guide-rollers 21 and the upper free run of which is also held in proper position by idlers 22 of usual construction. As the paper to be dried follows along with the hard felt apron 12 it can be very readily introduced between the band 20 and the first drying roll D at the left hand end of the machine, and the web will then travel along 25 with this band and be conducted thence over the second and lower roller D' while at the same time means are provided whereby the paper web 20 will be scraped from the first roller D in case a break should occur, these means consisting substantially of a scraper 26 as shown. The paper web 20 is now conducted into contact with the lower roll D' of which there are a series and which are peripherally engaged by a band or apron 27 which is supported by idlers 28. After passing the first lower roller D' the paper is conducted to the second upper roller D of the series where it is again held in contact with the periphery thereof by the band 20. 105 If now a break should occur between the

first lower roller D' and the second upper roller D, the paper web will be stripped from the former by a scraper 26 which is so inclined as to lead the paper toward the band 20 just before the latter engages the second upper roller of the series, and in order to bring the paper into what may be termed "forcible" contact with the band or apron 20 at that point, I employ an air-blast 10 which is generated by a blower B which may be of any desired construction and which has a blast-pipe b extending along the machine and connected at proper points with transversely disposed air-pipes 30 each of 15 which has preferably a slot at that portion of its wall which is nearest to the ductors or scraper plates 26, said slots extending for substantially the entire length of the transverse portion of said pipe. Supposing that 20 a break in the web should occur between the first roller D and the first lower roller D', the rotation of the upper roller D will strip the broken end from said roller, so that the latter will then hang gravitatively and 25 finally come in contact with the periphery of the first lower roller D' which will then naturally carry the web along until it is impinged between the surface of said roller and the band 27.

30 The construction and operation of the machine thus far described in connection with the first rollers, is substantially the same for the other rollers of the machine and until the web has reached the end thereof where the web is guided under a roll 35 and thence passes beneath a "grid" g of ordinary construction, and consisting of a series of longitudinally disposed blades 36 which are held by a bracket 37 attached to 40 the frame. At this point a scraper 38 is employed for stripping the web from the last upper roller D and an air-blast pipe is also disposed at this point so as to have its slot slightly inclined upward so that the air forced through said slot will blow the loose web along the underside of the grid and into 45 engagement between the first two rolls of a calendering machine which is indicated herein by C and the construction of which 50 may be of any desired form.

Inasmuch as the purpose of the present machine is: to dry the paper thoroughly before it enters the calendering rolls, the air-blast employed with the present machine 55 may be either hot or cold as desired, so that in either case the air-blast will in itself constitute an additional means whereby the web is dried. And as will be perceived on reference to the drawing, the direction of 60 the air blast is such relatively to the apron 20, a lower course of which travels in upward and then downward directions between the lower drier drums as to effect a drying of such apron as well as a drying of the web.

65 Many changes may be made in the con-

struction and organization of some of the coöperative elements of the machine without departing from the spirit of the invention.

I claim:

1. The combination with a series of rollers 70 and a web supply, of a stripper for stripping the web from one of said rollers and an air blast directed against said stripper for conducting the end of the web into contact with the next roller of the series. 75

2. The combination with a series of drying rollers, and a series of calendering rollers, of means for stripping a web from the last of the drying rollers, and an air-blast directed against the stripping means for 80 conducting the end of said web to the first of the calendering rollers.

3. The combination with a plurality of rollers, of a stripper contacting with one of 85 said rollers, an air supply pipe extending longitudinally of the last named roller adjacent the point at which said stripper is located, said pipe delivering a blast against the face of said stripper.

4. The combination with a web-supply, a 90 series of rollers successively operative on the web, and aprons connected with said rollers, respectively, for maintaining the web in contact therewith, of an air-blast for conducting the incoming end of the web 95 between the next roller of the series and the apron coöperative therewith.

5. The combination with a web-supply and sets of superposed rollers for operating upon the web, and means for maintaining the web in contact with the peripheries of 100 said rollers, respectively, of means for disengaging the web from the rollers at a point between two successive rollers, and an air-blast directed against said disengaging 105 means for bringing the stripped web between the next roller of the series and the web-retaining means coöperative therewith.

6. The combination with a web-supply, a 110 series of rollers disposed in superposed pairs for operating upon the web, and an endless apron coöperative with the upper set of rollers and having a partial peripheral contact with each roll of said series, of stripper plates for removing the web as it ascends 115 from the lower roll toward the upper roll, said stripper-plate extending from the periphery of the lower roll to the apron coöperative with the upper roll, and means for propelling the web along the stripper-plate, 120 to bring the same between the periphery of the upper roll and the apron coöperative therewith.

7. The combination with a web-supply, a 125 series of rollers disposed in superposed pairs for operating upon the web, and an endless apron coöperative with the upper set of rollers and having a partial peripheral contact with each roller of said series, of stripper plates for removing the web as it ascends 130

from the lower roll toward the upper roll, said stripper-plate extending from the periphery of the lower roll to the apron co-operative with the upper roll, and an air blast for propelling the web along the stripper-plate to bring the same between the periphery of the upper roll and the apron co-operative therewith.

8. The combination with web supply, a series of rolls arranged in superposed pairs, and endless aprons co-operative with said sets of rollers, respectively, and for causing the web to travel therewith, of means for removing the web from said rollers, respec-

tively, air-pipes disposed longitudinally of 15 said rollers, and having a perforation toward the stripper-plates, and an air-pressure supply connected with said pipes and for forcing air through said perforations to feed the web over the stripper-plates and into 20 contact with the next roller of the series.

Signed by me at Springfield, Mass., in presence of two subscribing witnesses.
